FIG. 7 is a bottom view of the yellow jacket stationery tab shown in FIG. 1.

U.S. PATENT DOCUMENTS

The long and short broken lines around the inside edge of the yellow jacket stationery tab define the bounds of the claimed design and form no part thereof.

D106,671 S * 10/1937 Mace D20/30
D169,633 S * 5/1953 Riddle D20/41
D256,601 S * 8/1980 Zacherle D21/606
D394,418 S * 5/1998 Schumacher et al. D11/162
D488,970 S * 4/2004 Kelleghan D8/38

The evenly spaced broken lines showing the clip and apertures in the middle of the yellow jacket stationery tab are included to show features that form no part of the claimed design.
